UNITED STATES PATENT OFFICE.

MADISON J. LORRAINE, OF SAN FRANCISCO, CALIFORNIA.

TAPE-SPLICE.

1,168,657.

Specification of Letters Patent. Patented Jan. 18, 1916.

Application filed September 2, 1913. Serial No. 787,706.

To all whom it may concern:

Be it known that I, MADISON J. LORRAINE, a citizen of the United States, residing in the city and county of San Francisco and State of California, have invented 5 a new Tape-Splice, of which the following is a specification.

The object of my invention is to provide means of uniting or mending sections of 10 metal tapes in a simple, accurate manner; and especially means for mending them quickly and satisfactorily in the field where the breakage occurs without the use of cumbersome tools, rivets, or solder. I do this 15 by means of a perforated infolding metal splice-sleeve in which the ends of the tape sections are inserted and are secured with rigid tongues formed from the metal of the tape itself and engaging with the metal of 20 the sleeve at the sides of the perforations.

My invention is illustrated in the accompanying drawings, in which—

Figure 1 is a plan view showing one section of a tape after it has been secured in 25 the splice-sleeve, and with the other section in line with the sleeve but not entered therein; Fig. 2 is a side view of the same. Fig. 3 is a plan view of the splice-sleeve. Fig. 4 is a cross section of the splice-sleeve. 30 and secured section of the tape. Fig. 5 is a perspective view of the splice-sleeve. Fig. 6 shows the splice-sleeve and contained section of tape placed in a punch preparatory to forming the tongue from the tape and 35 securing it therewith to the sleeve.

Similar numerals refer to the same or like parts in the figures.

The splice-sleeve is indicated in the figures by the numeral 1, and is designed to 40 accurately hold the tape sections so that when they have been joined there will be no normal, lateral, or longitudinal play and the tape will be true to alignment and length. It is formed with one side, or its 45 base, solid except for the perforations, and with the other side preferably open but having flanges 5, 5, and at the joint of the "mend," extensions or lugs 6, 6 intended to strengthen the sleeve at that point. The 50 sleeve infolds the tape sections closely holding them true laterally and normally. In the base of the sleeve perforations, or openings, 3, 3 are formed, of any practicable shape, but preferably triangular, each to 55 receive a corresponding shaped tongue 4, which is cut from the metal of the tape 2, as

with a suitable tool and is forced downward and crosswise through its opening until its point extends slightly beyond the outer face of the sleeve base, as indicated in 60 Figs. 2 and 4. In the operation of cutting the tongues from the tape the perforated base of the splice-sleeve becomes a die-plate and the sides of the openings 3, 3 which are adjacent to the extremities 65 become shoulders against which their opposed edges of the tongues bear and prevent the withdrawal of the tape sections from the sleeve, as the tongues are integral with the tape and rigid.

The operation of uniting, or mending, the sections of a tape is, as follows: One extremity of the tape section is inserted, endwise, in the splice-sleeve until it comes about in 70 the middle of the sleeve under 6, 6. The 75 splice-sleeve and contained tape is then placed under a properly formed punch until opening 3 is exactly under the cutting point of the punch and will act as a die. The punch is then struck, or forced downward, 80 until it cuts the tongue 4 from the metal of the tape section forcing it through the opening 3 and inclined downward where it will remain and will bear against the metal of 85 the base of the sleeve at the side of the opening 3 effectually securing the tape section to the sleeve. After one section of the tape 90 has been secured, as described, the other section is inserted in the opposite end of the splice-sleeve until its extremity abuts solidly against the end of the secured section and the operation of forming the second tongue and forcing it within and into engagement with the side of its corresponding 95 splice-sleeve opening is performed the same as for the first section. After both sections 100 have been secured, as described, the united tape will be true to length and alignment and the parts will be permanently united and can not be separated by any pull which 105 may be exerted in making measurements; and the whole operation of uniting them will consume a minimum amount of time, avoiding annoying and costly delays. The apparatus used is also simple and easily carried 105 as the splice-sleeves can be kept in a vest pocket and the punch, which will be small, can be attached to a key ring or carried loose in a pocket.

The essential features of the invention are 110 the infolding perforated splice-sleeve forming a die-plate, and its openings dies and

the sides thereof shoulders, and the integral, rigid tongues formed from the metal of the tape forced within the openings and their edges bearing against the sides of the same to secure the tape sections to and prevent their withdrawal from the splice-sleeve.

Having thus described my invention what I claim as new and desire to secure by Letters Patent, is—

1. A means of accurately uniting and splicing, sections of metal tapes consisting of an infolding, perforated splice-sleeve, the sides of the perforations forming shoulders which engage with the edges of rigid tongues punched from and remaining integral with the metal of the tape sections and forced within the perforations to cause said engagement.

2. A means of accurately uniting and splicing, sections of metal tapes consisting of an infolding splice-sleeve having perforations in its base, said perforated base acting as a die-plate in the formation of rigid tongues from the metal of the tape sections the edges of which tongues engage with the sides of the perforations to secure the tape sections within and to the splice-sleeve.

3. A means of accurately uniting and splicing, sections of metal tapes consisting of an infolding splice-sleeve, the extremities of the tape sections abutting against each other within the sleeve to which they are secured by means of rigid tongues punched from the metal of the tape sections and forced into openings in the sleeve and their

edges interlocking with the metal of the sleeve at the sides of the openings.

4. A means of accurately uniting and splicing, sections of metal tapes consisting of an infolding splice-sleeve within which the extremities of the tape sections abut against each other, one side of the splice-sleeve having lateral flanges and the opposite side being perforated and acting as a die-plate in the formation of rigid tongues from the metal of the tape sections, the said tongues being forced within the perforations and their edges engaging with the metal of the sleeve base at the sides of the perforations to secure the sections within and to the splice-sleeve.

5. A means of accurately uniting abutting sections of metal tapes consisting of a splice-sleeve closely infolding the tape sections, the splice-sleeve having perforations which act as dies the sides of which form shoulders; and tongues punched from and remaining integral with the infolded tape sections by means of the dies, and of like size and shape thereto, and forced within the perforations and remaining inclined and rigid therein their edges engaging with and bearing against the shoulders thereof to hold the tape sections fixed within the sleeve and prevent their longitudinal separation under tension.

MADISON J. LORRAINE.
